UNITED STATES PATENT OFFICE.

RAINER HERMANN POTT, OF DRESDEN, GERMANY, ASSIGNOR TO CHEMISCHE FABRIK
POTT & CO., OF DRESDEN-N., GERMANY.

TREATING AND WETTING OUT FIBROUS MATERIAL.

No Drawing. Original application filed July 26, 1924, Serial No. 728,494, and in Germany July 10, 1923.
Divided and this application filed September 23, 1925. Serial No. 58,184.

This invention has reference to improvements in the art of treating fibrous material, textile and similar goods, leather and the like with a view of increasing their liquid-absorbing, 5 penetrating and imbibing qualities, and it is particularly intended to devise means of overcoming the difficulty of uniform penetration of the goods in the employment of acid baths for the preparation of the material in various branches of the textile, leather and 10 allied industries which for various purposes are used in the presence of soaps, oils, sulphurized oils and preparations produced therefrom which in various methods of treatment, for example in the scouring, bucking or 15 steeping of fibrous material are employed both for the purpose of improving the wetting out effects as well as with a view of arriving at a uniform absorption of the coloring 20 matters in the dyeing of fibrous material and in similar or equivalent methods of treatment.

In the branches of the fiber treating art where use is made of acid liquors for the conversion or preparation of the material, as for 25 instance in the carbonization of woolen fabrics there is the difficulty that the acid liquor is frequently not evenly distributed in view of the rather water-repellent qualities of the fiber so that the acid liquor will be unevenly 30 distributed on and throughout the particular goods under treatment, and this difficulty is further increased by the presence of soaps and fatty substances or of unsaponifiable oily or 35 fatty material. This is particularly noticeable in the treatment of preliminarily washed goods, when the rinsing water contained therein is unequally distributed.

In accordance with my invention these 40 difficulties will be overcome by the employment of salts of the sulphur acids and aromatic compounds, particularly of sulphonates of the naphthalene series or of hydrogen-addition products thereof, such as tetrahydro- 45 naphthalene and combinations and compounds thereof. When these salts are added to the acid liquor and the material is immersed therein or is otherwise treated with the acid liquor and with the sulphonates referred to, the uniformity of distribution of

the treating liquor as well as of the soaps, oils and other substances used in the fiber-treating art is vastly increased. At the same time the sulphonated compounds referred to appear to have a kind of emulsifying or dissolving action and, by this means, the speed and uniformity of penetration are augmented and assisted, so that the presence of soaps and fatty residues is no longer an obstacle to the wetting out of fibrous material. The sulphonates referred to may be used alone or in combination with each other and/or in combination with hydrocarbons, alcohols or ketones, particularly with high molecular alcohols. Besides, the sulphonates employed 55 are adapted to increase the vividity of colors and, on the other hand, they act as a protective agent for preventing any injurious action of acids and any decomposition and depositing of soaps or saponaceous products. These 60 advantages among other uses will produce particularly favorable results in the acid-fulling of the cloth and felt industries, in the carbonization of wool, in the treatment of leather and as an addition to acid finish dyes 65 (wool dyeing).

As an instance of carrying the invention into practise I may add a few grams of tetrahydronaphthalene —B— sodium sulphonate to a liter of an acid bath in the presence of 80 hydrocarbons or of high molecular alcohols. I may also use as an instance alkyl derivatives of such sulphonates, such as for instance isopropyl naphthalene sodium sulphonate.

Obviously, the invention is not restricted to 85 the particular substances and ways of treatment herein mentioned by way of exemplification only and the invention may be embodied in modifications thereof, so as to suit particular working conditions and the nature 90 of the goods under treatment, and without deviating from the scope and the spirit of the invention, except as stated in the appended claims.

I claim:—

1. The process of treating fibrous materials, which comprises adding sulphonic acid salts of substituted aromatic polynuclear hydrocarbons to an acid fiber treating bath.
2. The process of treating fibrous materi- 100

als, which comprises adding sulphonic acid salts of substituted naphthalenes to an acid fiber treating bath.

3. The process of treating fibrous materials, which comprises adding sulphonic acid salts of iso-propyl naphthalene to an acid fiber treating bath.

4. The process of treating fibrous materials, which comprises subjecting such materials to the action of an acid bath to which 10 the sodium salt of iso-propyl naphthalene sulphonate acid has been added.

RAINER HERMANN POTT.
